VARIABLE RESISTANCE DEVICE

Sidney R. Greene, New Haven, Conn., assignor to Bendix Aviation Corporation, Teterboro, N. J., a corporation of Delaware

Application October 15, 1952, Serial No. 314,921

7 Claims. (Cl. 201—52)

The present invention relates to control devices for electrical circuits and more particularly to a variable resistance device for making fine and accurate resistance adjustments.

An object of the present invention is to provide a novel variable resistance device of few and simple parts for making fine and accurate resistance adjustments.

The present invention, therefore, contemplates a novel and simple variable resistance device which comprises a resistor element in the form of a coil spring and a member adapted to travel between the convolutions of the spring. The member is interposed between a pair of adjacent convolutions and is urged in a direction to compress a portion of the spring so as to effect engagement of the convolutions of said portions. Means are provided for effecting relative movement between the spring and the member, as to effect an increase or a decrease in the number of convolutions engaged, to vary the effective resistance of the device.

The above and other objects and advantages of the present invention will appear more fully hereinafter from a consideration of the detailed description which follows, taken together with the accompanying drawing wherein one embodiment of the invention is illustrated.

In the drawing:

Figure 1 is a view, in section, of one form of a variable resistance device embodying the present invention; and

Figure 2 is an exaggerated view of a disc-like member used with the variable resistance device of Figure 1.

Referring now to the drawing for a more detailed description of the present invention and more particularly to Figure 1 wherein one embodiment hereof is clearly illustrated, a variable resistance device, generally designated by the numeral 11, comprises a cylindrical container 12 of suitable insulating material provided with spaced end walls 14 and 15. End wall 15 may be cemented, for example, to container 12, or secured thereto in any suitable manner, to "close-off" the container. Disposed within container 12 is a resistor element, or a resistance wire, in the form of a coil spring 17 which may be helical, as shown in Figure 1. The ends of spring 17 protrude through openings 18 formed in end walls 14 and 15 and portions of the ends are fixedly secured to the walls, in any suitable manner, such as for example, by adhesive material. The ends of spring 17 may be connected to a pair of conductors (not shown) to connect device 11 in an electrical circuit.

Projecting through an aperture formed in end wall 15, and extending axially of spring 17, is a shaft 19 of an adjusting member 21. Member 21 has a slotted head 23 which is engageable by a suitable tool to provide rotation of the shaft. Shaft 19 has a rectangular-shape portion 24 which cooperates with a rectangular slot 25 (Figure 2) formed in a disc-like member 26, to support the latter for rotation with the shaft. Portion 24 is "peened" to prevent separation of member 26 and the shaft, but the dimensions of slot 25 and portion 24 are such that the disc-like member may have a "wobbling" motion, in addition to being rotatable with the shaft.

Disc-like member 26 is interposed between a pair of

2

adjacent convolutions of spring 17 and has a pair of diametrically opposed ears 30 (Figure 2) which engage the convolutions. It may be understood that the pitch of spring 17 provides for threading of disc-like member 26 between the convolutions of the spring, upon rotation of adjusting member 21, as to effect movement of member 26 axially of the spring. Arranged on shaft 19 and extending axially of spring 17 is a compression spring 32 which engages disc-like member 26 and urges the latter in a direction to provide compression of part of spring 17 (Figure 1), whereby the adjacent convolutions thereof engage each other and thus substantially short circuit each other. The force exerted by spring 32 is greater than the force offered by spring 17, and since the ends of the latter spring are fixed, the other part of the spring is expanded, whereby the convolutions thereof are disengaged.

To vary the effective resistance of device 11, adjusting member 21 is rotated in one direction or the other, so that the ears 30 travel between the convolutions of the spring to decrease, or increase, the number of convolutions engaged, or disengaged. It is apparent that the effective resistance of the device is a function of the number of convolutions engaged, or disengaged, so that an increase in the number of convolutions engaged, provides for decreased resistance while a decrease in the number of convolutions engaged, provides for increased resistance.

It may now be understood that the present invention provides a novel and effective variable resistance device of relatively few parts for making fine and accurate resistance adjustments. By providing a rotatable spring-pressed disc-like member between a pair of adjacent convolutions of a resistance coil spring, the number of convolutions engaged, or disengaged, may be varied without the use of threaded parts, and the like.

Although one embodiment of the invention has been illustrated and described in detail it is to be expressly understood that the invention is not limited thereto. Various changes can be made in the design and arrangement of the parts without departing from the spirit and scope of the invention as the same will now be understood by those skilled in the art.

I claim:

1. A variable resistance device of the class described comprising a resistor element in the form of a coil spring having a plurality of convolutions, a member interposed between a pair of adjacent convolutions of said spring, said member engaging at least one convolution of said pair and providing compression of a part of said spring whereby the convolutions thereof engage each other and providing expansion of the other part of said spring whereby the convolutions thereof are disengaged, and means providing relative movement between said spring and said member to vary the number of convolutions engaged, or disengaged, to thereby vary the effective resistance of the device.

2. A variable resistance device of the class described comprising a resistor element in the form of a helical spring, a disc-like member interposed between a pair of adjacent convolutions of said spring and having extending portions thereof engaging at least one convolution of said pair, spring means urging said disc-like member in a direction to compress a portion of said spring whereby the convolutions thereof are engaged, and means mounting said disc-like member and operable for displacing the latter axially of said spring to vary the number of convolutions engaged.

3. A variable resistance device of the class described comprising a resistor element in the form of a helical spring having a series of normally spaced convolutions, a rotatable shaft extending axially of said spring, a disc-like member mounted on said shaft for rotatable move-

ment therewith and interposed between a pair of adjacent convolutions of said spring, said disc-like member having a pair of extending portions engaging at least one convolution of said pair, and resilient means urging said disc-like member to compress a part of said spring whereby the convolutions thereof are engaged and to expand the other part of said spring whereby the convolutions thereof are disengaged, said shaft being rotatable in either direction to provide travel of said disc-like member between the convolutions of said spring to decrease or increase the number of convolutions engaged, or disengaged, depending upon the direction of rotation of said shaft, to vary the effective resistance of the device.

4. A variable resistance device of the class described comprising a hollow cylindrical container of insulating material having end walls, a resistor element in the form of a helical spring within the container and having its ends fixed to said end walls, a rotatable shaft extending axially of said helical spring, a disc-like member mounted on said shaft for rotation therewith and interposed between a pair of adjacent convolutions of said helical spring, a spring operatively connected with said disc-like member and urging it in a direction to compress a part of said helical spring whereby the convolutions thereof are engaged and to provide expansion of the other part of said helical spring whereby the convolutions thereof are disengaged, said shaft being rotatable to provide travel of said disc-like member between the convolutions of said helical spring to decrease or increase the number of convolutions engaged or disengaged to vary the effective resistance of said device.

5. A variable electrical impedance device comprising an electrical impedance element in the form of a coil spring having a plurality of convolutions, means including a member interposed between a pair of adjacent convolutions of said spring and in engagement with a convolution of said pair for providing compression of a part of said spring whereby the adjacent convolutions thereof engage each other substantially to short circuit each other and for providing expansion of the other part of said spring whereby the convolutions thereof are disengaged, and means for moving said member between the convolutions of said spring and along the axis thereof to vary the number of convolutions engaged, or disengaged, and thereby vary the effective impedance of the device.

40

6. In a variable electrical impedance device, a coil spring having a plurality of turns of electrically conductive material distributed along the axis of the spring, a member disposed between a pair of adjacent turns of said spring and in engagement with the spring so that some turns are compressed with the adjacent turns of the compressed turns engaging each other and substantially short-circuiting each other and other turns of said spring uncompressed with the uncompressed turns out of engagement with each other, and means for threading said member between the turns of said spring in one direction along said axis so that for predetermined increasing axial positions of said member in said one direction an increasingly fewer number of turns are compressed and short-circuited and for threading said member between the turns of said spring in the opposite direction along said axis so that for increasing axial positions of said member in said opposite direction an increasingly larger number of turns are compressed and short-circuited.

7. A variable electrical impedance device comprising an impedance element in the form of a coil spring having a plurality of convolutions, a member interposed between a pair of adjacent convolutions of the spring and engaging at least one convolution of said pair, means urging said member in one direction to compress a part of said spring whereby the adjacent convolutions thereof engage each other substantially to short circuit each other and to provide expansion of the other part of said spring whereby the convolutions thereof are disengaged, and means for operating said member for travel between the convolutions of said spring in said one direction to compress additional convolutions of the spring so that additional convolutions engage each other to decrease the effective impedance of said device and in the opposite direction to provide a reduction in the number of convolutions which engage each other to increase the effective impedance of the device.
